UNITED STATES PATENT OFFICE.

JOSEPH GABRIELLA, OF GORHAM, COLORADO.

FLAG-WHEEL FOR RADIATOR-CAPS.

1,291,472.

Specification of Letters Patent. Patented Jan. 14, 1919.

Application filed September 26, 1918. Serial No. 255,762.

To all whom it may concern:

Be it known that I, JOSEPH GABRIELLA, a citizen of the United States, residing at Gorham, in the county of Boulder, State 5 of Colorado, have invented a new and useful Flag-Wheel for Radiator-Caps; and I do hereby declare the following to be a full, clear, and exact description of the invention, such as will enable others skilled in the art 10 to which it appertains to make and use the same.

The present invention relates to a display attachment for automobile radiator caps, and has for its object to provide a device 15 of this character which embodies novel features of construction whereby it can be readily clamped upon a conventional cap and provides a moving display which is of a pleasing character and will attract attention.

20 Further objects of the invention are to provide a device of this character in which the display elements are mounted upon a revolving member driven by a wind wheel so that the parts are positively driven while 25 the automobile is in motion, which can be easily assembled or taken apart, which is not liable to break or get out of repair, and which provides an effective means for displaying the national flag in association with 30 the flags of friendly countries.

With these and other objects in view, the invention consists in certain novel combinations and arrangements of the parts as will 35 more fully appear as the description proceeds, the novel features thereof being pointed out in the appended claims.

For a full understanding of the invention, reference is to be had to the following description and accompanying drawings, in 40 which:—

Figure 1 is a vertical sectional view through a radiator cap attachment constructed in accordance with the invention.

Fig. 2 is a top plan view of the same with 45 the revolving disk removed.

Fig. 3 is a front elevation of the device, showing it as mounted upon the radiator cap at the front of an automobile.

Corresponding and like parts are referred 50 to in the following description and indicated in all the views of the drawings by the same reference characters.

Referring to the drawings, which illustrate one possible embodiment of the invention, the reference character A designates 55 an open frame which is of a proper size to fit around and inclose the conventional cap of an automobile radiator. The frame may be formed with two complementary side bars 1 which have the intermediate portions 60 thereof correspondingly bowed or deflected outwardly, the ends 1^a of the bars at the front of the frame being extended forwardly in a spaced and parallel relation and having a pair of bearing blocks 2 arranged 65 between the same and secured in position in any suitable manner as by means of the fastening members 3, while the opposite ends 1^b of the bars project rearwardly and are connected by a clamping bolt 4. A series 70 of arms 5 project inwardly from the upper edge portion of the open frame A, said arms being radially disposed with respect to the frame and terminating at their inner ends in upwardly projecting flanges 5^a which are 75 secured by fastening members 6 to a centrally disposed block 7.

Projecting upwardly from the block 7 is a stud 8 upon which the hub 9^a of a disk 9 is rotatably mounted. A cap 10 is fitted 80 upon the upper end of the stud 8 and serves to hold the disk 9 in position thereon, and the periphery of the disk is formed with a depending annular rack 11 which meshes 85 with a pinion 12. This pinion 12 is rigid with a short horizontal shaft 13 which extends forwardly from the frame A and is journaled within the bearing blocks 2, the rear end of the shaft being provided with a head 14, while the forward end thereof terminates in a reduced threaded portion 13^a upon which the hub of the wind wheel 15 is threaded. The wind wheel and head 14 hold the shaft 13 against longitudinal movement, and the wind wheel faces the front of 90 the radiator so that when the motor vehicle is in motion the air will act upon the wind wheel to rotate the same. The pinion 12 is driven in this manner, and motion is imparted from the pinion to the disk 9, thereby causing the disk to revolve continuously 95 while the motor vehicle is in motion.

The display includes a central flag 16 carried by a staff 17 which has the lower end

thereof secured in an opening in the pivot stud 8, and a series of smaller flags 18 carried by staffs 19 which have the lower ends thereof swiveled in the rim portion of the 5 disk 9 at intervals in the periphery thereof. For this purpose the rim of the disk is provided with openings 20 which loosely receive the lower ends of the staffs 19, and also with small bosses 21 surrounding the mouths 10 of the openings. Caps 22 are fitted removably upon the bosses 21 and engage collars 23 on the flag staffs 19 to hold the flag staffs against vertical displacement. It will be obvious, however, that the flag staffs are free 15 to rotate about a vertical axis, and that as the disk 9 rotates the flag staffs will also revolve in order that the flags may at all times stream rearwardly in the direction of the wind.

20 In fastening the device to a radiator cap, the open frame A is placed around the cap and the overhanging rim portion of the cap caused to be engaged by claws 24 which are dependent from the arms 5. These claws 25 may be conveniently formed from tongues which are stamped from the arms and pressed downwardly. When thus constructed the claws will have a certain amount of resiliency for bringing about a firm engagement with the radiator cap, and by tightening the clamping bolt 4 the sides of the frame can be drawn together to bring the claws into a tight gripping engagement with the cap. The wind wheel 15 is arranged to 30 face the front of the motor vehicle, so that it will be acted upon by the air to drive the shaft 13 and rotate the disk 9 when the motor vehicle is in motion. The flags or other display elements carried by the rotatable disk will thus be kept in motion and displayed in an attractive and most effective manner.

Having thus described the invention, what I claim as new and desire to secure 45 by Letters Patent, is:—

1. An attachment for automobile radiator caps including a clamping frame surrounding the cap, a block supported over the frame and provided with a pivot stud, a 50 horizontally disposed disk journaled on the pivot stud and provided with a peripheral rack, display elements carried by the disk, a pinion meshing with the rack, and a wind wheel operatively connected with the pinion 55 for driving the same to rotate the disk.

2. An attachment for automobile radiator caps including a clamping frame surrounding the cap, a block supported over the frame and provided with a pivot stud, a 60 horizontally disposed disk journaled on the pivot stud and provided with an annular rack, a series of staffs projecting upwardly from the disk and swiveled thereto, flags carried by the staffs, a pinion engaging

the rack of the disk, and a wind wheel 65 operatively connected to the pinion for driving the same.

3. An attachment for automobile radiator caps including a clamping frame surrounding the cap and formed in complementary 70 sections of which the forward ends are extended in a spaced relation, a pair of bearing blocks secured between the said forward ends, a short shaft journaled between the bearing blocks, a pinion rigid with the shaft 75 and arranged between the bearing blocks, a wind wheel rigid with the forward end of the shaft, a block supported over the frame and provided with a pivot stud, a horizontally disposed disk journaled on the 80 pivot stud and provided with an annular rack meshing with the pinion, and display elements carried by the disk.

4. An attachment for automobile radiator caps including a clamping frame surrounding the cap, a block arranged over the frame, arms projecting inwardly from the frame and secured to the block, depending claws projecting from the arms for engaging the cap, a horizontally disposed disk 90 journaled on the block and provided with a peripheral rack, display elements carried by the disk, a pinion meshing with the peripheral rack of the disk, and a wind wheel 95 having an operative connection with the pinion.

5. An attachment for automobile radiator caps including a clamping frame surrounding the cap, a block arranged over the frame, a series of arms projecting inwardly 100 from the frame and secured to the block, claws projecting downwardly from the arms and arranged for engagement with the radiator cap, a horizontally disposed disk journaled on the block, a central flag staff projecting upwardly from the block, a series of flag staffs projecting upwardly from the periphery of the disk and having a swivel connection thereto, flags on the flag staffs, a wind wheel carried by the frame, and a 110 driving connection between the wind wheel and the disk.

6. An attachment for automobile radiator caps including a clamping frame surrounding the cap and formed of complementary 115 side bars having the intermediate portions thereof correspondingly bowed, the forward ends of the bars being extended forwardly in a spaced relation, a pair of spaced bearing blocks secured between the forwardly 120 extending ends of the bars, a clamping bolt connecting the rear ends of the bars, a short shaft journaled upon the bearing blocks, a pinion rigid with the short shaft and arranged between the bearing 125 blocks, a wind wheel applied to the forward end of the short shaft, a block supported centrally over the frame, arms pro-

jecting inwardly from the frame and secured to the block, claws carried by the arms for engaging the radiator cap, a horizontally disposed disk journaled on the block and provided with a peripheral rack meshing with the before mentioned pinion, and display elements carried by the disk.

In testimony whereof I have signed my name to this specification in the presence of two subscribing witnesses.

JOSEPH GABRIELLA.
